UNITED STATES PATENT OFFICE.

JOSEPH HURST, OF LOUISVILLE, KENTUCKY.

CENTRIFUGAL PUMP.

1,034,456.

Specification of Letters Patent.

Patented Aug. 6, 1912.

Application filed December 9, 1911. Serial No. 664,795.

To all whom it may concern:

Be it known that I, JOSEPH HURST, a citizen of the United States, residing at Louisville, in the county of Jefferson and State 5 of Kentucky, have invented certain new and useful Improvements in Centrifugal Pumps, of which the following is a specification.

This invention relates to centrifugal pumps designed more particularly for dredging 10 purposes, and its object is to provide the blades of the runner with removable wear blocks of novel form and construction, so that when they are worn away from the sand, gravel and other hard substances passing 15 through the pump, they may be removed and replaced by new ones.

The invention also has for its object to provide wear blocks which are arranged so as to increase the capacity of the pump.

20 In the accompanying drawing forming a part of this specification—Figure 1 is a front elevation of the pump runner. Fig. 2 is an edge view thereof. Fig. 3 is a vertical section on the line 3—3 of Fig. 2. Fig. 4 is an elevation showing a modification. Fig. 5 is an edge view thereof. Fig. 6 is a vertical section on the line 6—6 of Fig. 5.

Referring specifically to the drawing, the 30 pump runner comprises two laterally spaced circular disks 10 and 11, respectively, carrying therebetween the blades 12. The disk 10 has a central opening 13 which is the inlet, and the disk 11 has a hub 14 whereby the runner is mounted on the drive shaft 15.

35 The blades 12 extend radially and have their outer ends flush with the periphery of the runner disks. The inner ends of the blades terminate at a point close to the inlet opening and carry wear blocks 16 which 40 project a short distance into the plane of said opening. The blocks form the tips of the blades, and their main body portion has a thickness and shape to form a solid continuation of the blades. The blocks also 45 have an extension 17 of reduced thickness which fits on the working face of the blades and terminates flush with the outer ends thereof. The blocks therefore not only form a solid continuation of the inner ends or 50 tips of the blades, but also form the working faces thereof.

The inner ends of the blades to which the wear blocks are secured, and the contiguous ends of said blocks, are reduced in thickness,

and in said reduced portions are alined 55 openings to receive bolts 18 for fastening the blocks to the blades. The bolt heads are countersunk in the working face of the blocks, so that there will be no projecting parts to interfere with the proper working 60 of the blades. The nuts 19 which secure the bolts are screwed against the rear face of the blades. The reduced portion of the blocks and the contiguous portion of the blades are undercut so that a more rigid 65 connection may be had.

Figs. 4 to 6 show a modified form of wear blocks 20 having extensions 21 similar to the extensions 17, but prolonged so as to project beyond the plane of the periphery of 70 the runner disks as indicated at 22, and on the side edges of said projecting ends are flanges 23 which fit the periphery of the runner disks and form continuations thereof. By these projecting extensions the capacity 75 of the pump is increased. The blocks 20 are fastened to the blades 12 in the same manner as the blocks 16.

1. A runner for centrifugal pumps comprising laterally spaced disks, one of said 80 disks having a central inlet opening, blades mounted between the disks and terminating short of the aforesaid inlet opening, and removable wear-blocks mounted on and covering the entire working face of the 85 blades and projecting from the inner ends of the blades into the plane of the inlet opening, said projecting portions of the wear-blocks within the plane of the inlet opening having a thickness and shape to 90 form solid continuations of the blades.

2. A runner for centrifugal pumps comprising laterally spaced disks, one of said 95 disks having a central inlet opening, blades mounted between the disks, and removable wear blocks secured to the inner ends of the blades and having extensions which fit on the blades and form the working face thereof, said extensions projecting beyond the plane of the periphery of the disks, and 100 having side flanges fitting said periphery.

In testimony whereof I affix my signature in presence of two witnesses.

JOSEPH HURST.
